UNITED STATES PATENT OFFICE.

GEORGE J. WASSON, OF PITTSBURGH, PENNSYLVANIA.

SANITARY COVER FOR TOILET SEATS.

Application filed June 30, 1927. Serial No. 202,652.

This invention relates to a sanitary cover for toilet seats, one of the objects being to provide a device of this character formed of tissue and having connected thereto attaching means for engagement with the seat, thereby to hold the cover firmly in place, the said attaching means being formed of a material which will disintegrate quickly in water although normally of sufficient stiffness to provide efficient attaching means.

A further object is to provide a device of this character, which after once being used, can be discarded in the hopper without danger of choking the same.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

In said drawings,

Figure 1 is a bottom plan view of the cover, the fastening means being shown folded thereagainst.

Figure 2 is a side elevation showing the cover connected to a seat.

Figure 3 is an enlarged section through a portion of the seat showing one of the fastening means in engagement therewith.

Referring to the figures by characters of reference 1 designates a sheet of tissue shaped to properly cover a seat S and attached to the bottom surface of this cover close to the margin thereof by means of an

adhesive are hook-shaped tabs 2 having long bills 3 extending inwardly toward the center of the cover, these tabs being normally flat against the surface of the cover as shown particularly in Figure 1. Each of the tabs is formed of a material which will quickly soften and disintegrate when placed in water but, under normal conditions, is of sufficient stiffness to constitute an efficient fastening means. Each tab is adapted to be bent along a score line 4 so that the hook portion thereof will extend perpendicularly to the cover. After being thus located the several hooks of the tabs are placed in engagement with the lower surface of the seat S at the margin thereof, thereby to hold the cover firmly in position as shown particularly in Figures 2 and 3. The bill is so shaped as to fit snugly against the bottom of the seat and the remaining portion of the tab will overhang the marginal portion of the seat as shown particularly in Figure 3.

It will be understood that after the cover has been used it can be readily removed, crumpled up and discarded by throwing it into the water in a hopper where it will dissolve quickly. Prior to use the cover can be folded into a small package so as to be carried readily.

What is claimed is:

A device of the class described including a cover of tissue and seat engaging hooks of a normally stiff material adapted readily to disintegrate in water, said hooks being normally folded flat against the cover and being shiftable to position perpendicular thereto for engagement with the marginal portion of the seat.

In testimony that I claim the foregoing as my own, I have hereto affixed my signature.

GEORGE J. WASSON.
